(57) **CLAIM**

We claim the ornamental design for a wall-mounted lighting fixture, as shown and described.

DESCRIPTION

FIG. 1 is a front perspective view of a wall-mounted lighting fixture;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1; and,

FIG. 7 is a bottom view of the design of FIG. 1.

The broken lines in FIGS. 1, 3, 4, 6 and 7 form no part of the claimed design.
